UNITED STATES PATENT OFFICE.

RICHARD R. HARRIS, OF OCEAN BEACH, CALIFORNIA.

ARTIFICIAL LIMB AND HARNESS THEREFOR.

Application filed May 19, 1923. Serial No. 640,278.

To all whom it may concern:

Be it known that I, RICHARD R. HARRIS, a citizen of the United States, and residing at Ocean Beach, San Diego, in the county of San Diego and State of California, have invented certain new and useful Improvements in Artificial Limbs and Harness Therefor, of which the following is a specification.

10 My present invention relates to improvements in artificial limbs and harness therefor, and it is more especially intended to provide an apparatus comprising an artificial leg which is supported at the shoulder of the wearer and serves as a crutch, tending to take practically all of the weight off the stump of the wearer which is usually highly sensitive.

15 It is well known that the wearers of wooden legs are loath to use the same and often prefer crutches on account of the sensitive nature of the stump, and it is for their relief that the present invention is designed.

20 25 My invention will be more fully understood after reference to the accompanying drawings, in which like parts are indicated by similar reference symbols throughout the several views, and in which:—

30 Figure 1 is a front elevation of the apparatus as applied to a wearer, the wearer being indicated in dotted lines;

35 Figure 2 is a similar view to Figure 1, except as seen from the left of said figure;

40 Figure 3 is a side elevation of the knee joint and connected parts, and on a larger scale than in Figures 1 and 2, the parts being shown in the standing position, that is with the knee straight;

45 Figure 3^a is a similar view to Figure 3, but shows the parts in the position as when the knee is bent, or as in walking;

Figure 4 shows a section along the line 4—4 of Figure 3, and looking in the direction of the arrows;

50 Figure 5 shows a section along the line 5—5 of Figure 3, and looking in the direction of the arrows;

Figure 6 shows a section along the line 6—6 of Figure 3, and looking in the direction of the arrows;

55 Figure 7 is a detail view on a still larger scale than in the preceding figures, shows

the compression spring for use in returning the knee joints to the erect position;

Figure 8 shows a side elevation, on a larger scale, of the crutch support for the shoulder;

Figure 9 is a side elevation of the parts shown in Figure 8;

Figure 10 is a side elevation of the thigh joint, the parts being shown with the thigh straight in full lines, and with the thigh bent forwards in dotted lines;

Figure 11 shows a section along the line 11—11 of Figure 10, and looking in the direction of the arrows;

Figure 12 is a detail view showing the ankle joint, with the artificial foot shown in full lines in the vertical position and in dotted lines in the inclined position;

Figure 13 is a sectional view along the line 13—13 of Figure 12, and looking in the direction of the arrows; and

Figure 14 shows a section along the line 14—14 of Figure 12, and looking in the direction of the arrows.

The complete apparatus comprises a jointed crutch arrangement extending from beneath the crotch of the arm of the wearer down to and including an artificial foot, and the various parts will be described beginning at the top.

A represents a crotch piece which is preferably in the form of an arc of a circle, or adapted to fit beneath the shoulder of the wearer, which is lined or covered with yielding material *a*, such as rubber, or a pneumatic pad, or the like. This crotch is provided with a downwardly projecting arm *a'* terminating in the ball *a^o* which fits in the socket *b^o*, provided at the upper end of the metal strip *B*, which is adjustably connected as by means of the clamps *C* and clamp screws *c* to the metal strip *D* to which the belt *E* is secured.

80 85 90 95 This belt is preferably formed partly of metal and partly of leather, or webbing, or other suitable flexible material; the rear portion *e* being in the form of a metal strip secured to the strip *D*, and the front portion *e'* being preferably in the form of leather, or webbing, and adjustably connected to the body of the wearer by means of the buckle *e²*.

100 Hinged to the strip *D*, as by means of the bolt *f*, is the upper thigh piece *F*, which nor-

mally projects downwards, and is secured to the lower thigh piece F' by means of the clamps G and clamp screws g . The upper thigh piece F carries a band H , preferably made partly of metal, such as h and partly of leather, webbing, or other flexible material, such as h' , which band is adjustably secured to the wearer as indicated in dotted lines in Figures 1 and 2. This stump is 5 preferably encased in a suitable sack I open at both ends, and adjustably secured to the stump by means of the straps and buckles i see Figure 1. This sack is preferably made 10 of flexible material, such as knit webbing, or the like, and the upper end of the sack is suspended from the belt E by means of suitable adjustable straps J , with buckles j .

The lower thigh piece F' is adjustably connected to the upper thigh piece F as already 20 described, and is pivoted near its lower end, as at K , to the upper member M of the leg piece, the lower member M' of which is adjustably connected to the upper member by means of the clamps N and screws n . The 25 lower member M' of the lower leg piece is pivoted as at p to the foot socket piece P , which carries the leaf spring Q , said socket piece and leaf spring being preferably encased in felt, rubber, or other suitable material R , which forms the outline for the foot.

The foot socket piece P is shown in detail in Figures 12 to 14, and is provided with two side walls p' , flanged laterally at the bottom 35 as at p^2 to receive the leaf spring Q , which is held in place by the set screws q ; and at its upper end it is provided with ends p^3 flanged inwardly as shown in Figures 13 and 14 to provide stops for the member M' , 40 already referred to. The foot socket piece P is connected to the member M and to a similar strip M^2 , which is also pivoted on the bolt p near its opposite end, and passes up on the opposite side of the leg, being adjustably secured to an upper member M^3 by means of the clamps N' and set screws n' .

Connecting the members M and M^3 is a band S , and connecting the members M' and M^2 is the band S' , and connecting these 50 bands S and S' , and shaped conformably to the sound leg of the wearer, are the front and rear adjustable strips M^4 and M^5 , see Figures 1 and 2. There is thus formed a skeleton leg and foot for the wearer over 55 which the stocking and other garments may be worn.

In order to complete the socket for the stump of the wearer, I provide on the inner side of the leg strips F^2 and F^3 corresponding 60 to the strips F' , and the strips F' and F^2 are connected together by a band T , and the strips F^3 and F are connected together by the belt H already referred to. The strips F^2 and F are also connected together by one 65 or more bolts f^6 , and thus a frame-work is

provided to receive the stump of the wearer, but it is not intended to take up any of the substantial weight of the wearer except on the continuous crutch arrangement formed at the side of the apparatus. 70

In Figures 1 and 2 I have shown the right leg of the wearer removed by an operation above the knee, and the stump is indicated in dotted lines, but the parts of the apparatus adjacent to the stump would be constructed 75 and arranged so as to fit any stump according to any of the ordinary above the knee amputations, whether high or low.

The operation of swinging the stump forward would ordinarily flex the knee joint of 80 the artificial leg, and when the step forward is completed the parts are restored to the original or straight position shown in Figure 2, by means of a suitable compression spring arrangement shown in Figures 2, 3, 3^a, 5 and 85 7, in which S^0 is a cross piece on the band S provided with a socket s^0 adapted to receive the tapered end u of the casing U , in which the spring U' is held under compression, as by means of the piston U^2 held beneath the 90 cap u' . This piston carries a rod u^2 having the yoke u^3 , engaging the pin t which spans the two arms T' projecting downwardly from the band T , see Figures 3, 3^a and 5. Flexing the knee joint will cause the spring 95 U' to be still further compressed, and this spring will tend normally to straighten the leg when the step is completed.

There is limited play at the knee joint between the reinforced abutting surfaces f^2 and 100 m^2 , see Figure 3^a, and there is similar play allowed as seen at the left of Figure 10. The various joints may be supplied with buffers of rubber or other suitable material if desired. 105

The foregoing description is intended to explain the normal application and use of the leg in walking; but in order to permit the wearer to seat himself comfortably and remain seated without having the artificial 110 leg projecting forward in a more or less straight and stiff condition, I provide the releasing attachment which will now be described.

W represents a loop of cord, or chain, or 115 other flexible material, which passes around the shoulder of the wearer and is normally held in place by an outer garment, such as a shirt, coat or the like, and this loop is provided with a downwardly extending line 120 W' . This line terminates in a spring plunger V , carried by the guides V' , see Figures 3, 3^a and 4, and this plunger has a rounded head v which engages in the notch x in the bearing plate X in which the knee pivot K is mounted. At each end of this 125 notch stops x' and x^2 are provided which will limit the swinging movement of the strip M and the parts carried thereby to a predetermined angle, and thus the knee joint 130

cannot ordinarily be flexed beyond said angle.

Now in sitting down it is desired to still further flex the knee joint, and this may be accomplished by lifting or shrugging the shoulder carrying the loop W. This shrugging of the shoulder will lift the head v from engagement with the notch x, and while the lower leg may not be flexed forward more than through a small angle, it may be flexed backwards as desired.

In order to prevent the premature lifting of the plunger V, from any cause, the line W' is led through suitable guide or fair leaders Y in the harness.

When the parts are assembled and mounted on the wearer, as indicated in Figures 1 and 2, the mere throwing forward of the stump will flex the knee joint as in the normal operation of walking, and the knee joint will be straightened out again by means of the compression spring U', and practically all of the weight of the wearer will be transmitted from the crotch under the arm pit down to the foot support, and thus there will be practically no weight at all thrown on the sensitive stump of the wearer.

When the wearer desires to sit down, after seating himself by simply shrugging or lifting on the shoulder supporting the loop, the knee joint may be broken so as to permit the artificial leg to be swung backward to the position taken when the wearer is seated.

Thus it will be seen that I provide a lower leg which is in the form of a light metal skeleton with the resilient foot joint, and with flexible knee and hip joints, and the arrangement is such that when the weight of the wearer is thrown upon the artificial leg it is supported from the shoulder of the wearer and not from the stump as heretofore. By the herein-described arrangement the use of the ordinary crutch is entirely unnecessary for a one-legged man, and he may walk with freedom either with or without a cane.

It will be noted that the various parts of the device are adjustable so that the artificial leg and harness therefor may be satisfactorily adjusted to fit the individual wearer, and a few standard sizes only will be needed in order to fit wearers of ordinary height or configuration.

It will be obvious that the herein described apparatus is suitable for use either on men or women, and may be readily fitted to a wearer of either sex.

It will be obvious that various modifications might be made in the herein-described apparatus, and in the construction, combination and arrangement of parts which could be used without departing from the spirit of my invention, and I do not mean to limit the invention to such details except as particularly pointed out in the claims.

Having thus described the invention what is claimed as new and desired to be secured by Letters Patent is:

1. Apparatus of the character described, comprising a frame provided with a series of adjustable metal supporting strips hinged together to form a flexible crutch extending substantially from the arm pit of the wearer to the ground, with a crotch piece connected to the head of the upper strip by a universal joint, and a foot piece connected to the lower end of the lower strip, with means for connecting said frame to the body of the wearer.

2. Apparatus of the character described, comprising a frame provided with a series of metal supporting strips hinged together to form a flexible crutch extending substantially from the arm pit of the wearer to the ground, the said frame comprising a vertical body member with means for attaching same to the body of the wearer, a thigh member hinged to said body member, a lower leg frame hinged to said thigh member, a spring normally tending to throw said leg frame in alignment with said thigh member, and a foot piece carried by said leg frame.

3. Apparatus of the character described, comprising a frame provided with a series of metal supporting strips hinged together to form a flexible crutch extending substantially from the arm pit of the wearer to the ground, a crotch piece in the form of a padded yoke adapted to engage under the arm pit of the wearer, a ball and socket joint connecting said crotch piece to the head of the upper strip, and a transversely disposed foot piece hinged to the lower end of the lower strip, with means for connecting said frame to the body of the wearer.

4. Apparatus of the character described, comprising a frame provided with a series of adjustable metal supporting strips hinged together to form a flexible crutch extending substantially from the arm pit of the wearer to the ground, with a crotch piece in the form of a padded yoke connected to the head of the upper strip by a universal joint, and adapted to engage under the arm pit of the wearer, and a transversely disposed resilient foot piece pivoted to the lower end of the lower strip, with means for connecting said frame to the body of the wearer.

5. Apparatus of the character described, comprising a crotch piece adapted to engage under the arm pit of the wearer, a frame provided with a series of metal supporting strips hinged together to form a flexible crutch extending substantially from the arm pit of the wearer to the ground, the said frame comprising a vertical body member with means for attaching same to the body of the wearer, a thigh member

hinged to said body member, a lower leg frame hinged to said thigh member, a spring normally tending to throw said leg frame in alignment with said thigh member, and in alignment with said thigh member, and 5 a transversely disposed resilient foot piece hinged to said leg frame at the lower end thereof.

6. Apparatus of the character described, comprising a frame provided with a series 10 of adjustable metal supporting strips hinged together to form a flexible crutch extending substantially from beneath the shoulder of the wearer to the ground, the said frame comprising a vertical body member with 15 means for attaching same to the body of the wearer, an adjustable thigh member hinged to said body member, a lower leg frame hinged to said thigh member, a spring plunger located entirely in the space be- 20 tween the thigh member and the lower leg frame and normally tending to throw said leg frame in alignment with said thigh member, and a transversely disposed resilient foot piece carried by said leg frame, with a 25 crotch piece adapted to engage in the arm pit of the wearer and connected to the upper end of said frame by a universal joint.

7. Apparatus of the character described, comprising a vertical body member with 30 means for attaching same to the body of the wearer, a thigh member hinged to said body member, a lower leg frame hinged to said thigh member, means for limiting the angular movement of said lower leg frame relative to said thigh member, and means operable by the shoulder of the wearer for re- 35 leasing said limiting means when desired, and a spring plunger located entirely in the space between the thigh member and the lower leg frame and normally tending to 40

throw said leg frame in alignment with said thigh member, and a foot piece pivoted to said leg frame.

8. Apparatus of the character described, comprising a vertical body member with 45 means for attaching same to the body of the wearer, a thigh member hinged to said body member, a lower leg frame hinged to said thigh member, a notched plate carried by 50 said leg member, and a spring plunger carried by said thigh member and normally en- gaging said plate for limiting the angular movement of said lower leg frame relative to said thigh member, and a loop mounted over the shoulder of the wearer with a cord 55 connecting said loop and said plunger for disengaging said plunger from said notched plate when desired.

9. Apparatus of the character described, comprising a vertical body member with 60 means for attaching same to the body of the wearer, a thigh member hinged to said body member, a lower leg frame hinged to said thigh member, a notched plate carried by 65 said leg member, and a spring plunger car- ried by said thigh member and normally en- gaging said plate for limiting the angular movement of said lower leg frame relative to said thigh member, and a loop mounted over the shoulder of the wearer with a cord 70 connecting said loop and said plunger for disengaging said plunger from said notched plate when desired, means normally tending to throw said leg frame in alignment with said thigh member, and a foot piece hinged 75 to said leg frame.

In testimony whereof I hereunto affix my signature.

RICHARD R. HARRIS.
